EXIT LATCH.

Application filed November 22, 1924. Serial No. 751,486.

The present invention relates to latches and more particularly to mechanism for normally latching the exit doors of public buildings, such as schoolhouses, theaters, and office buildings.

Modern construction of public buildings, such as schoolhouses, favors the employment of wide opening exits, which facilitate emptying of the building in case of fire or other disaster. These exits may be closed by double doors which open outwardly. The doors are held at top and bottom by mechanism which may be released through a simple pressure upon a cross bar or pedal to unlatch and open the doors in a single operation.

The object of the present invention is to reorganize and improve exit latches of this general type in order to simplify the cost of manufacture and installation and at the same time improve the construction and operation of the latch.

With this and other objects in view, the several features of the invention consist in certain novel features of construction, combinations and arrangements of parts hereinafter described and claimed, the advantages of which will be obvious to those skilled in the art from the following description.

In the accompanying drawings illustrating the preferred form of the invention Fig. 1 is a partial elevation of an exit door with the improved type of latch applied thereto; Fig. 2 is a side elevation of the latch shown in Fig. 1 applied to the door; Fig. 3 is a detail illustrating the center housing with the bottom plate removed and the spindle operating mechanism enclosed therein; Fig. 4 is a vertical section upon the line 4—4 of Fig. 3 illustrating another view of the spindle operating mechanism; Fig. 5 is a detail of either the upper or lower housing illustrating the latch and operating mechanism partly in section; and Fig. 6 is a section upon the line 6—6 of Fig. 5 illustrating the mechanism shown in Fig. 5.

According to the present invention, an operating instrumentality such as a pedal or cross bar is connected with the upper and lower spindles through a double toggle lever in such a manner that outward movement of the operating instrumentality moves the upper and lower vertical spindles or rods in opposite directions. The operating spin-

dles at their upper and lower ends respectively project into housings of similar form and construction having locking latches pivotally mounted therein. The spindles are loosely connected with the latch bolts in such a manner that movement of the spindles in a direction to release the latches withdraws the latter against the action of light springs. On the other hand pressure directly upon the latches and connected bolts, caused by engagement between the latches and striker plates on closing the doors, does not compel a like movement of the vertical spindles and operating mechanism. The present construction is greatly simplified as compared with existing commercial constructions designed for the same purpose, is rugged and efficient in its operation, and is capable of operating repeatedly for long periods without undue wear or injury to the parts. Furthermore, the failure or breakage of any one of the operating springs does not interfere with the release of the lock.

Referring to the illustrated embodiment of the invention, the latch mechanism comprises generally upper and lower operating rods or spindles 10 and 12 projecting into latch housings 14 and 16. The inner ends of the spindles are connected into a center housing 18 provided with an operating pedal 20. The latches projecting from the upper and lower housings 14 and 16 engage with striker plates 22 mounted upon the upper and lower door jambs. It will be observed that with this construction the latch comprises essentially a center housing and two vertical spindles and latch housings of identical form and shape. As indicated clearly in Figs. 3 and 4, the center housing 18 has an operating pedal 20 pivoted therein at 22. The operating instrumentality is provided with a tail 24 which engages in a slot 26 formed in a tubular head 28. The head 28 is pivoted at 30 to a pair of toggle links 31 and 32 which in turn are connected at their outer ends to a second pair of toggle links 34 and 35. This second pair of toggle links is pivoted at 36 to an upper head 38. The upper and lower heads are mounted for sliding movement in openings formed in the housing 18, as indicated clearly in Fig. 4. The pivotal connections of the two pairs of toggles indicated at 40 and 42 are supported by swinging links or arms 44 and 45 which are in turn pivoted at their opposite ends 110

within the housing 18. These pivotal connections are formed by studs 48 and 49. With this construction, a depression or outward movement of the operating instrumentality 20 elevates the head 28 and through the interconnected toggles depresses the head 38 elongating the springs 50. This reverse movement of the head 38, as contrasted with the head 28, is caused by the two pairs of toggles which assume the approximate positions shown in dotted lines in Fig. 3, the supporting links 31 and 32 swinging outwardly to accommodate the spreading movements of the pivotal connections. This construction forms an exceedingly simple and efficient mechanism for imparting releasing movements to the upper and lower spindles through the actuation of the single operating instrumentality 20. The upper and lower spindles 10 and 12 are respectively connected with the heads 38 and 28, the spindles having threaded ends 60 which engage within similarly threaded bores 62 formed in the heads. This form of connection permits the effective length of the spindles to be adjusted and accommodate variations in the over-all height of the doors. The opposite ends of the spindles project within the latch housings 14 and 16, as indicated more particularly in Figs. 5 and 6. Each latch housing is provided with a latch member 70 pivoted therein at 72 and having a sliding latch bolt 74 connected with the latch at 76. The latch is provided with a cam face 78 which engages with a similarly curved surface formed upon a striker plate 79 to prevent movement of the latch in the direction of the arrow in Fig. 6. Depression of the latch shown in Fig. 6 permits opening of the door. Upon closing the door, the latch is readily depressed through engagement with the outer portion of the striker plate and depression of the latch about the pivotal connection 72. The latch is normally retained in locking position by a light spring 80 surrounding the latch bolt 74 and interposed between the head of the bolt and a web 82 formed in the housing. The latch bolt projects through an opening in the web 82 and is provided with a head 84 upon its lower end, which is engaged by a hook 86 formed upon a head 88, which in turn is secured to the end of the operating spindle. The movement of the operating spindle toward the center housing causes the release of the latch through the latch bolt 74. Upon releasing the operating instrumentality 20, the spindles are returned to inoperative position through the springs 50 and the latches are returned to operating position through the springs 80. The outward movement of the latches is preferably limited by a dog 90 mounted within the latch housing and engaging with the head 84, as indicated clearly in Fig. 6. It will be evident to those

skilled in the art that the latch housing indicated in Figs. 5 and 6 is shown in position on the upper portion of a door. The same housing is employed for latching the lower edge of the door by merely reversing its position. Upon closing the door, both latches are moved inwardly upon engagement of the cooperating striker plates. This movement is not, however, communicated to the spindles and operating mechanism, due to the fact that the latch bolts and heads 84 are free to move inwardly without causing a corresponding movement of the spindles and connected heads 88. This construction prevents unnecessary movement and wear upon the operating parts, due to repeated opening and closing of the door. In order to protect the operating mechanism for the spindles from dust and dirt, the housing 18 is preferably closed by a bottom plate 100 shown in Fig. 4, which is mounted in a recessed portion of the housing to permit the latter to be attached directly to the side of the door through the threaded members 102. If so desired, the operating spindles may be guided intermediate their ends by guides 104 provided with openings for the passage of the spindles and secured to the door by threaded fastenings 106.

As will be evident, the present construction is rugged and relatively easy to install and when so installed is positive in its operation and capable of satisfactory operation for long continued periods.

While it is preferred to employ the specific construction and arrangement of parts shown and described, it will be understood that this construction and arrangement is not essential except so far as specified in the claims and may be changed or modified without departing from the broader features of the invention.

The invention having been described, what is claimed is:

1. Latching mechanism for exit doors comprising two operating rods extending vertically across the door, latches connected with opposite ends of the rods, a center housing into which the adjacent ends of the rods extend, an operating instrumentality on the center housing, and connections within the housing for moving the rods in opposite directions on actuation of the instrumentality, comprising two links connected at their adjacent ends to one another and at their opposite ends to the rods to form a jointed lever and a pivoted arm connected to the joint of the lever at the free end of the arm to permit swinging movement of the joint in a direction transverse to the direction of movement of the ends of the lever while constraining the joint against movement in the direction of movement of the heads.

2. Latch mechanism for exit doors comprising an operating instrumentality, a hous-

ing in which the operating instrumentality is pivoted, heads sliding within the housing, connections between the operating instrumentality and one of the heads, two pairs of toggle links extending transversely of the heads and connecting the heads intermediate their ends, and means for supporting the toggles during movement of the heads toward and from one another.

10. 3. Latch mechanism for exit doors comprising two operating rods extending vertically of the door, latches connected with opposite ends of the rods, a center housing into which the adjacent ends of the rods extend, an operating instrumentality on the center housing, connections within the housing for moving the rods in opposite directions on actuation of the instrumentality, comprising two sets of toggle levers interconnected at their outer ends and connected with the respective heads at the joints intermediate their ends, and supporting arms extending lengthwise of the housing and connected at their free ends to the outer ends of the interconnected toggle levers to limit movement of the outer ends of the levers lengthwise of the housing while permitting movement of the outer ends transversely of the housing.
20. 4. Latch mechanism for exit doors comprising a center housing, upper and lower heads sliding within the housing, an operating instrumentality pivoted in the housing having a projection connected with the lower head, a pair of toggle levers connected together at their outer ends and each con-

nected intermediate its ends to the upper and lower heads respectively, means for limiting the outer ends of the toggle levers against movement lengthwise of the housing, and means for normally separating the heads.

5. Latch mechanism for exit doors comprising a center housing, heads slidingly mounted in opposite ends of the housing, a pair of toggle levers interconnected at their outer ends and connected with the respective heads intermediate their ends, means for limiting the movement of the outer ends of the toggle levers lengthwise of the housing, means for normally moving the heads apart, and manually operated means for moving the heads toward one another through the interconnected toggle levers.

6. Latch mechanism for exit doors comprising a center housing, heads slidingly mounted in opposite ends of the housing, a pair of toggle levers interconnected at their outer ends and connected with the respective heads intermediate their ends, means for limiting the movement of the outer ends of the toggle levers lengthwise of the housing, means for normally moving the heads apart, manually operated means for moving the heads toward one another through the interconnected toggle levers, oppositely disposed latches, and connections between the sliding heads and latches to retract the latches upon movement of the heads toward one another.

In testimony whereof I have signed my name to this specification.

J. OTTO SOEMER.
